CAN END EMBOSsing MECHANISM

Frederick W. Duhan, Philadelphia, Pa., assignor,
by mesne assignments, to Crown Cork & Seal
Company, Inc., Baltimore, Md., a corporation
of New York

Application August 10, 1951, Serial No. 241,195

3 Claims. (Cl. 101—6)

1

The present invention relates to a marking machine for marking container or can parts which are interposed between cooperating rotary marking heads.

An object of the invention is the provision of a marking machine with cooperating rotary marking heads which are mounted for rotation on overhanging shafts supported by bearing means on both sides of the marking heads. The provision of two bearings supporting each marking head assembly provides rigidity to the marking mechanism without the use of large diameter marking heads. Since this provision allows the use of smaller diameter marking heads, it, therefore, eliminates the necessity of an accelerated feed mechanism as used in the past to carry a can part or end through the marking assembly using the large marking heads mounted on a shaft supported by a single bearing.

Another object of the invention is to provide each marking assembly with a separate housing member. One housing member carrying one marking head is fixed with respect to the frame of the machine, whereas the other housing member and its corresponding marking head is pivotal and yieldable. Since one of the marking heads is yieldable with respect to the other marking head, the occurrence of a jam or damage to the marking heads is eliminated should foreign material or an imperfect can part be fed into the machine.

A still further object of the invention is the provision of a marking head having easily interchangeable embossing dies or type pads. Interchangeability of the dies or type pads gives the machine more utility and adaptability.

A further object of the invention is providing overhanging spaced shafts for supporting the marking heads. This provision allows the use of positive means for conveying or feeding container parts or ends through the marking heads to a can covering or seaming machine.

These and other objects of the invention will appear more clearly from the accompanying drawings in which:

Figure 1 is a plan view of the marking machine.

Figure 2 is an enlarged vertical sectional view taken on the line 2—2 of Figure 1.

Figure 3 is a front elevational view with parts shown in section.

Figure 4 is an end elevation viewed from the right of Figure 1 and with parts shown in section substantially on the line 4—4.

Figure 5 is an enlarged sectional plan view taken on the line 5—5 of Figure 2.

Figure 6 is a fragmental detail view in the same direction as Figure 2.

2

Figure 7 is a transverse sectional detail taken on the line 7—7 of Figure 6.

Figure 8 is a further detailed sectional view similar to Figure 7.

Figure 9 is an enlarged detailed plan view of the marking head.

Figure 10 is a vertical sectional view taken on the line 10—10 of Figure 9.

Figure 11 is a detailed face view of the die plate mounted in an element of the marking head.

Figure 12 is an edge view of Figure 11.

Figure 13 is a central sectional view taken on the line 13—13 of Figure 11.

In the preferred embodiment of the invention as shown in the drawings, the marking machine is of the type having cooperating rotary marking heads with marking elements inserted therein for embossing or printing suitable identifying markings on can ends or closures. If the container or can part is to be embossed, cooperating male and female embossing dies are used, but the invention is not limited to embossing as type pads may be inserted in one head and backing pads in the other for printing on the container or can part. The can ends are supplied from a suitable storage rack to a trackway where they are fed by a positive drive conveyor to the marking heads. After suitable identifying markings are placed on the can ends, the ends are then fed to a turret which supplies them to a can closure or seaming machine.

Referring specifically to the drawings wherein like reference characters represent like or similar parts, the can or container parts 10 are stored in a storage rack, generally designated 12, mounted on the frame 28 of the machine. Beneath the can end storage rack 12 is a guideway 14 consisting of two parallel tracks which support the can closures by their peripheral edges as they are conveyed through the machine. The tracks or guideway 14, which is attached to the upper section of the frame 28, extends from beneath the rack 12 longitudinally through the machine between the marking heads 16 and to the turret 18 and can seaming machine, generally designated 20.

The positive means for conveying the can ends 10 along the guideway or tracks 14 and through the marking heads 16 consists of an endless conveyor assembly 22 having a chain drive 24 and a plurality of conveyor arms 26. The conveyor assembly 22 is mounted on the frame 28 of the machine adjacent to the tracks or guideway 14. Spring means, generally designated 30, are provided for adjusting the tension of the chain drive 24 by longitudinally moving the idler sprocket 55

wheel 23. Each of the conveying arms 26 of the conveyor assembly 24 extends transversely of the parallel tracks 14. The arms 26 have at their ends a lip portion 32 which extends upwardly into the plane of the parallel tracks 14, and this lip portion 32 engages the can end 10 to convey it from beneath the storage racks 12 to the can seaming machine 20. As best shown in Figure 2, the conveyor arms 26 and their lip portions 32 will pass between the marking heads 16 and, thus, positively convey the can end while it is being embossed. Any suitable source of power may be used to drive the conveyor assembly 22 by means of the sprocket wheel 25. However, it is noted at this point that the conveyor 22 and the marking heads 16 must be driven in a timed relationship with each other, in order that the identifying markings may be properly located on the can ends 10. This is accomplished by mounting the sprocket wheel 25 for rotation on the end of the shaft 60' which also drives one of the marking heads 16 keyed thereto. A more detailed description of the drive of the shaft 60' will follow in the specification.

Referring now to Figure 2, the marking heads 16 are mounted for rotation in separate housing members 34 and 36. A lower housing member 34 is fixed integral with the frame 28 of the machine, while the upper housing member 36 is pivoted to the lower housing member 34 by means of a pair of boss hinges 38 located on the lower housing and the pivot pin 49 (Figs. 3, 5 and 7). A more detailed description of the means of supporting the marking heads within each housing will follow in the specification. Since there is always a possibility of debris, foreign matter, imperfect can ends, or two can ends stuck together being fed to the marking heads 16 and causing a jam or damage to the marking elements 42, it is necessary and important to provide a pivotal housing 36 having yielding means so as to protect the smooth operation of the machine should this condition occur. As best shown in Figures 6 and 7, the yielding means for the pivotal housing 36 consist of a bolt or stud 44 mounted in a flange 46 located on the lower housing 34. The bolt or stud 44 extends through a transverse cut-out 48 of the flange 50 of the upper housing 36. Mounted on the bolt or stud 44 between the flange 50 of upper housing 36 and the adjustment nuts 54 of the bolt is a spring 52 which urges the upper housing 36 and its corresponding marking head 16' into operative engagement with the lower housing 34 and its corresponding marking head 16''. The adjustment nuts 54 provide easy adjustment of the tension of the spring 52. Thus, by constructing the upper housing so that it is yieldably pivotal with the lower housing, a jam may be prevented should foreign matter or an irregular can end be fed between the marking heads.

In addition to the provision of yieldable means for preventing a jam, a positive and manually operated means is provided for releasing an actual jam should this condition arise at the marking heads. The manual means for pivoting the upper housing 36 and releasing a jam at the marking heads consists of a lever 56 pivoted to the upper housing 36 and having a cam 58 at its end thereof bearing against the flange 46 of the lower housing member. An operator may thus manually release the marking heads from operative engagement with each other by merely pivoting the lever which, in turn, will pivot the upper housing 36 and its marking head 16' away from the lower housing 34 and its marking head 16''.

Supported for rotation on spaced parallel shafts 60 in each housing member is a marking head 16. The marking heads 16 are keyed to the rotating driving shafts 60 by means of keys 62. As stated prior in the specification, any suitable source of power which will drive the marking heads 16 and the conveyor 22 in timed relationship may be used. A source of power (not shown) drives a drive shaft 64 mounted in the frame 28. Located on one end of the drive shaft 64 is a beveled gear 66 which meshes with a beveled gear 68. The gear 68 is mounted on the end of a shaft 70 supported in the housing 34 by means of bearing 72. Also, mounted on the shaft 70 is a gear 74 which meshes with the gear 76 mounted on a shaft 78 supported by a bearing 80 in the upper housing 36. The ends of the shafts 70 and 78 are hollow and are provided with a keyway in order that they may be keyed to the shafts 60' and 60'' respectively by the key 62. The gear box 81 housing the bevel gears 66 and 68 and gears 74 and 76 may be lubricated by means of an oil bath or the like.

The spaced parallel shafts 60' and 60'', on which are keyed the marking heads 16, are supported in each housing in the same manner, and thus only the means of supporting the shaft in the upper housing will be described. A pair of bearings 82 and 84 mounted in the upper housing 36 support the shaft 60'' for rotation. The bearing 84 is mounted in cantilevered relationship with respect to the bearing 82 and this is made possible by designing the upper housing so that it has two side walls 86 extending from the body of the housing and having a connecting end wall 88. The bearing 84 is then mounted in the end wall 88. The purpose of mounting the bearings in this manner is to give rigidity to the marking heads when they are of small diameters. In the past, marking heads were made much larger in diameter to give the required rigidity to the assembly, because they were supported at one end only. By mounting the bearings 82, 84, 90 and 92 so that there is one bearing of a pair in cantilevered relationship to the other bearing of that pair also allows the shafts 60' and 60'' to be mounted in overhanging relationship. This is important in that the conveying arms 26 and the lip portion 32 must be able to pass through the marking heads 16 in order to obtain a positive means of feeding the can ends 10.

The marking heads 16' and 16'' are cylindrical and each carries a marking element 42 locked therein. The marking elements 42 will be a male and female die if it is desired to emboss the container part 10 or they may be type pads and a backing means if it is desired to print on the container part. Since it is desirable that the marking elements 42 be interchangeable, the marking head is made up of a plurality of interlocking cylindrical parts 96 having an arcuate segment 98 cut out for the reception of the dies or type pads A, B, C and D. The locking means consists of a circumferential bead and groove on each cylindrical part 96 and a circumferential groove on the marking element 42 which will cooperate with the bead of the adjacent cylindrical part 96. In other words, the groove 91 of cylindrical part 96 and the groove in the marking element 42 will cooperate with each other to receive the bead 93 of an adjacent cylindrical part 96 so that the marking element 42 will be interlocked with, and retained in, the arcuate segment 98 of cylindrical part 96. A pair of bolts 97 passing through apertures 99 in the

cylindrical parts 96 will retain the marking head 16 as a unit.

In order to remove a marking head 16 for replacement of dies, the shaft 60, supporting said marking head, must first be removed by means of a puller tool 61 threaded into the end of said shaft. The shafts 60 are held in place by means of a locking ring 63, and a manual pull on the shafts 60 will release them from position. Removal of the marking heads is completed by removing the cover plate 65 and removing them through the top of the housing.

The terminology used in the specification is for the purpose of description and not for limitation, the scope of the invention being defined in the claims.

I claim:

1. A can marking machine comprising a frame, a housing member rigidly mounted on said frame and having parallel side walls extending transversely therefrom and connected by an end wall, a second housing member pivoted to said first housing member and also having parallel side walls extending transversely therefrom and connected by an end wall, a pair of bearings mounted in each of said housing members, one of said bearings of each pair being mounted in the end wall of each of said housing members and in cantilevered relationship with the other bearing of said pair, the other bearing of each of said pairs being mounted in each of said housing members in axial alignment with the bearings mounted in said end walls, a pair of rotatable shafts supported at each end thereof by each pair of bearings, a marking head mounted on each of said shafts between the bearings, means in said housing members providing an opening through which said marking heads project, each of said marking heads having marking elements cooperating with each other for marking a can

end interposed therebetween, and means yieldably urging said second housing member and its marking head toward said first housing member and its marking head.

5 2. A can marking machine of the character described in claim 1 wherein manual means are provided for pivoting said second housing member with respect to said first housing member so that said marking heads are in an inoperative position, said means including a lever actuated cam pivoted to one of said housing members and engaging the other of said housing members for pivoting said housing members with respect to each other.

10 15 3. A can marking machine of the character described in claim 1 including means defining a guideway for said cam ends through the machine, driving means for feeding said can ends along said guideway and through said marking heads, said driving means also driving said marking heads in timed relationship to the feeding of the can ends.
